(57) CLAIM

I claim the ornamental design for a L.E.D. light, as shown and described.

DESCRIPTION

FIG. 1 is a perspective view of a light embodying my new design;

FIG. 2 is a top plan view thereof;

FIG. 3 is a left side elevational view thereof, the right side view being a mirror image of that shown;

FIG. 4 is a bottom plan view thereof;

FIG. 5 is a front elevational view thereof; and,

FIG. 6 is a rear elevational view thereof.

The portions of the design shown in dotted lines are not being claimed.
